DESIGN FOR A PIN OR SIMILAR ARTICLE

Rae C. Swain, South Gate, Calif., assignor to
S. P. Lerner, Los Angeles, Calif.

Application April 30, 1943, Serial No. 110,086

Term of patent 3½ years

To all whom it may concern:

Be it known that I, Rae C. Swain, a citizen of the United States, residing in South Gate, in the county of Los Angeles, State of California, have invented a new, original, and ornamental Design for a Pin or Similar Article, of which the following is a specification, reference being had to the accompanying drawing, forming a part thereof.

The essential features of my design reside in the parts shown in full lines.

I claim:

The ornamental design for a pin or similar article, as shown and described.

RAE C. SWAIN.
